[57] CLAIM

The ornamental design for a short bone retractor, as shown and described.

DESCRIPTION

FIG. 1 is a front perspective view of a short bone retractor, showing my new design;

FIG. 2 is a fragmentary perspective view of a second embodiment of the short bone retractor wherein the only difference resides in the appearance of the tip portion, the remaining portions being identical to that shown in FIGS. 1-7;

FIG. 3 is a top plan view of FIG. 1;

FIG. 4 is a right side elevational view of FIG. 1;

FIG. 5 is a rear elevational view thereof;

FIG. 6 is a left side elevational view thereof;

FIG. 7 is a bottom plan view thereof;

FIG. 8 is a top plan view of FIG. 2;

FIG. 9 is a fragmentary side elevational view of FIG. 2, the opposite side being identical thereof;

FIG. 10 is a fragmentary rear elevational view of FIG. 2;

FIG. 11 is a bottom plan view thereof;

FIG. 12 is a front elevational view of FIG. 1; and

FIG. 13 is a fragmentary front elevational view of FIG. 2.
